TOY ELEPHANT FIGURE

Harry Meth and Susan Lake, Cincinnati, Ohio, assignors to General Mills Fun Group, Inc., Minneapolis, Minn.

Filed Oct. 26, 1970, Ser. No. 25,670

Term of patent 14 years

Int. Cl. D21—01

U.S. Cl. D34—2

FIG. 1 is a perspective view of a toy elephant figure illustrating our new design;

FIG. 2 is a back view thereof;

FIG. 3 is a side elevational view thereof;

FIG. 4 is a front view thereof;

FIG. 5 is a top plan view thereof; and

FIG. 6 is a bottom plan view thereof.

We claim:

The ornamental design for a toy elephant figure, substantially as shown.
